(57) **CLAIM**

The ornamental design for a hand cart, as shown and described.

DESCRIPTION

FIG. 1 is a perspective view of a hand cart showing our new design;

FIG. 2 is a front view thereof;

FIG. 3 is a top view thereof;

FIG. 4 is a bottom view thereof;

FIG. 5 is a left side view thereof;

FIG. 6 is a right side view thereof;

FIG. 7 is a perspective view showing a second embodiment of our design;

FIG. 8 is a front view thereof;

FIG. 9 is a top view thereof;

FIG. 10 is a bottom view thereof;

FIG. 11 is a left side view thereof; and,

FIG. 12 is a right side view thereof.

The shading and tone in the reproductions are to represent relief or contours of surfaces of the three-dimensional products. The back view of each the design is omitted because it is a mirror image of the front view.
